D20-23

EX

OR D 3,678

RE 3678

PATENTED
SEP 28 1869

Witnesses

John B. Richardson
R. J. P. Goodwin

George W. Tucker

Manchester N.H.
for R. J. P. Goodwin
attorney

United States Patent Office.

GEORGE W. TUCKER, OF MANCHESTER, NEW HAMPSHIRE.

Design No. 3,678, dated September 28, 1869.

DESIGN FOR A TRADE-MARK.

The Schedule referred to in these Letters Patent and making part of the same.

I, GEORGE W. TUCKER, of Manchester, county of Hillsborough, and State of New Hampshire, have invented and produced a new and original Design for a Trade-Mark, of which the following is a specification.

My invention consists of a card or label, having in the centre the picture of an "anchor," beneath it the words "XXX Ale, Tucker & Co." Within the circle surrounding the above words are the following, "Anchor Brewery Manchester, N. H."

Claim.

I claim as my invention the design for a trade-mark, as described and shown.

Witnesses: GEORGE W. TUCKER.
                                  JOHN E. RICKFORD,
                                  RICHARD J. P. GOODWIN.